UNITED STATES PATENT OFFICE.

GEORGE ALEXANDER BURROUGHS, WILLIAM GRANT, AND ANTHONY PETER KUTCHAW,
OF SUDBURY, ONTARIO, CANADA.

ELECTRIC-HEATER.

1,202,509.

Specification of Letters Patent. Patented Oct. 24, 1916.

Application filed November 1, 1915. Serial No. 59,080.

To all whom it may concern:

Be it known that we, GEORGE ALEXANDER BURROUGHS, WILLIAM GRANT, and ANTHONY PETER KUTCHAW, subjects of the King of Great Britain, and residents of Sudbury, in the Province of Ontario, Dominion of Canada, have invented certain new and useful Improvements in Electric Heaters, of which the following is the specification.

10 This invention relates to improvements in electric water heaters and the objects of the invention are to provide a simple and effective water heater in which the water will be readily and quickly heated.

15 A further object is to construct a heater which will remain hot for a considerable time after the current has been turned off on the heating element.

With the above and other objects in view the invention consists essentially of the improved construction particularly described and set forth in the following specification and accompanying drawing.

In the drawing, Figure 1 is a longitudinal sectional elevation of the improved heater. Fig. 2 is a transverse section of the improved heater taken midway up of Fig. 1.

Like characters of reference indicate corresponding parts in all the figures.

30 Referring to the drawing, A represents the improved heater comprising the heating element 10 about which the water coil 11 is located, the said coil and heating element being housed in the water jacket 12 which is substantially cylindrical in cross section and terminates in a conically shaped head in the upper end.

The coil 11 communicates with the water jacket 12 through the medium of the outlet 13 while the heated water is discharged from the said jacket through the pipe 14. The several elements enumerated consisting of the heating element, the coil and water jacket are housed in a vacuum jacket 15 having a substantially conical upper end through which the discharge pipe 14 passes.

Cold water is delivered to the coil 11 through the inlet pipe 16 which passes through the vacuum jacket 15 and the water jacket 12. The lower end of the heater is fitted with a removable cover 17 having an asbestos lining 18 which serves as a heat insulating means and prevents radiation to the said cover, while current from any suitable source is supplied to the heating element through the wires 19 and 20.

The assembly of the heater will be readily understood from the foregoing description.

In using a heater of this description it is only necessary to turn on a supply of cold water which passing through the inlet 16 is delivered to the coil 11, where coming under the influence of the heating element 10 it is quickly brought to the desired temperature and delivered through the discharge 13 into the water jacket 12 from whence it is delivered through the discharge pipe 14.

The water jacket 12 performs a dual function in that besides subjecting a large volume of water to the influence of the heating element it prevents the inner face of the vacuum jacket 15 being unduly heated and liable to burn.

From the above it will be seen that the device is completely constructed and that the heat generated from the electric heating element 10 will effectively heat the water coil 11 as the heat is confined within the vacuum jacket 15 and hence is insulated from the exterior atmosphere. Further, after the current has been turned on for some time and the water heated the current may be switched off and the water in the coil will remain hot for at least twenty-four hours, due to its being completely insulated by the vacuum jacket.

What we claim as our invention is:

A water heater comprising a coil heater having its upper convolutions forming a substantial cone and its discharge pipe forming the apex of the cone, a water jacket surrounding the coil provided with a conical

upper end connected to the discharge end of the coil heater, a vacuum jacket provided with a conical upper end surrounding the water jacket, and a discharge pipe extending from the apex of the water jacket through the apex of the vacuum jacket, both of said discharge pipes registering with each other and having their adjacent ends spaced apart.

In witness whereof we have hereunto set our hands in the presence of two witnesses.

GEORGE ALEXANDER BURROUGHS.
WILLIAM GRANT.
ANTHONY PETER KUTCHAW.
